(57) **CLAIM**

The ornamental design for a display screen with graphical user interface in grid formation, as shown and described.

DESCRIPTION

FIG. 1 is a front view of a first embodiment of a display screen with graphical user interface in grid formation; and, FIG. 2 is a front view of a second embodiment of a display screen with graphical user interface in grid formation. The outermost broken line illustrates a display screen and forms no part of the claimed design. The remaining broken lines illustrate portions of the graphical user interface that form no part of the claimed design.
